US0D1047725S

(12) **United States Design Patent** (10) **Patent No.:** **US D1,047,725 S**
(45) **Date of Patent:** **** Oct. 22, 2024**

(54) **VACUUM GAUGE**

(71) Applicant: **AZBIL CORPORATION**, Tokyo (JP)

(72) Inventor: **Raita Mori**, Chiyoda-ku (JP)

(73) Assignee: **AZBIL CORPORATION**, Tokyo (JP)

(**) Term: **15 Years**

(21) Appl. No.: **29/753,330**

(22) Filed: **Sep. 30, 2020**

(30) **Foreign Application Priority Data**

Apr. 1, 2020 (JP) ..... 2020-006417 D

(51) **LOC (14) Cl.** **10-04**

(52) **U.S. Cl.**

USPC **D10/85**; D10/96

(58) **Field of Classification Search**

USPC D10/93, 86, 96; D23/235

CPC G01L 19/14; G01L 9/0072; G01L 19/04;
G01L 19/143

(57) **CLAIM**

The ornamental design for a vacuum gauge, as shown and
described.

DESCRIPTION

FIG. 1 is a rear, top, and left side perspective view of a
vacuum gauge showing the new design;

FIG. 2 is a rear, bottom, and left side perspective view
thereof;

FIG. 3 is a rear, top, and right side perspective view thereof;

FIG. 4 is a rear, bottom, and right side perspective view
thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side elevational view thereof; and,

FIG. 10 is a right side elevational view thereof.

The broken lines depict portions of the vacuum gauge that
form no part of the claimed design.

1 Claim, 8 Drawing Sheets
